LAPPING MACHINE

Herbert S. Indge, Westboro, Mass., assignor to
 Norton Company, Worcester, Mass., a corpora-
 tion of Massachusetts

Application May 14, 1936, Serial No. 79,755

15 Claims. (Cl. 51—122)

This invention relates to lapping machines, and more particularly to an improved machine for simultaneously lapping plane surfaces on a plurality of work pieces.

5 One object of this invention is to provide a simple and thoroughly practical lapping machine for simultaneously lapping a plane face on a plurality of work pieces. A further object of this invention is to provide a lapping machine 10 with a plurality of members which serve to yieldably hold a plurality of work pieces in operative engagement with the lap.

A further object of this invention is to provide 15 a readily accessible means for loading and unloading a portion of the work carrying cage while the lapping operation continues on work pieces in the remainder of the cage. A further object of this invention is to provide an indexing mechanism for the cage member which enables 20 indexing the cage to permit the same to be readily loaded from an operating station in front of the machine. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

30 In the accompanying drawings in which is shown one of various possible embodiments of the mechanical features of this invention,

Figure 1 is a vertical sectional view, taken 35 through the improved lapping machine, having parts shown in elevation;

Figure 2 is a fragmentary plan view of the machine, showing the arrangement of the work holding devices and the work cage;

40 Figure 3 is a fragmentary cross sectional view, on an enlarged scale, taken approximately on the line 3—3 of Fig. 2, showing the details of the lap, the cage and the work holding mechanism; and

45 Figure 4 is a fragmentary cross sectional view, on an enlarged scale, taken approximately on the line 4—4 of Fig. 1, showing the details of the one-revolution clutch.

A lapping machine has been illustrated in the 50 drawings comprising a base 10 which supports a rotatable lapping wheel 11. The rotatable lapping wheel 11 is mounted on a flanged member 12 which is keyed to a sleeve 13. The sleeve 13 is rotatably supported in bearings 14 and 15 in the base 10.

A driving mechanism is provided for rotating 55 the lapping wheel 11 at the desired lapping speed. This mechanism may comprise an electric motor 16 mounted on the base 10. The motor carries 60 a gear 17 mounted on the outer end of a motor

shaft 18. The gear 17 meshes with a gear 19 mounted on the outer end of a rotatable shaft 20 which is journaled in a bearing 21 in the base 10. A worm 22 is mounted on the inner end of the shaft 20 and meshes with a worm gear 23 which is keyed to the sleeve 13. When the motor is rotated, its rotary motion is transmitted through the shaft 18, the gear 17, the gear 19, the shaft 20, the worm 22, the worm gear 23, the sleeve 13, the flanged member 12, to rotate the lapping wheel 11 at the desired lapping speed.

A work holding cage 30 is provided for holding a plurality of work pieces 31 in engagement with the operative face of the lapping wheel 11 for a lapping operation. The cage 30 is arranged for movement relative to the rotatable lapping wheel and is preferably arranged for a reciprocatory motion relative to the lapping wheel 11 to carry the work pieces across the face of the lapping wheel during rotation thereof. A plurality of spaced guide pins 35 are supported in brackets 36 on a pan-shaped member 37. As illustrated in the drawings, four pins 35 are provided which are spaced at 90° from each other. The guiding pins 35 are adjustably supported on the brackets 36 and are held in adjusted position thereon by a screw 42. The cage member 30 is provided with a plurality of elongated slots 38 which cooperate with the pins 35 to guide the cage 30 during its reciprocatory movement. These elongated slots 38 are arranged parallel to each other and serve to hold the cage 30 against rotation while it is reciprocated across the face of the lapping wheel 11. Each of the studs 35 is provided with a fixed flange 39 which serves as a support for the lapping plate 30. Each of the studs 35 is also provided with a removable collar 40 and a nut 41 which serve to hold the cage in the desired operating relation with the supporting flanges 39.

In order to produce the desired reciprocatory motion of the cage 30 during a lapping operation, a crank movement may be provided comprising a crankpin 50 which is provided with an enlarged head 51. The enlarged head 51 rides in an elongated slot 52 in the center portion of the cage 30. The elongated slot 52 is arranged at substantially right angles to the elongated slots 38 so that when the crankpin 50 is revolved, the enlarged head 51 sliding in the elongated slot 52 causes the cage member 30 to reciprocate relative to the rotating lapping wheel 11.

A suitable driving mechanism is provided for rotating the crankpin 50 at the desired speed to cause the required reciprocation of the cage 30. The crankpin 50 is supported on a bracket 53 which is adjustably mounted on a rotatable head 54. The head 54 is keyed to a shaft 55 which is rotatably supported in bearings 56 and 57. The bearings 56 and 57 are formed within the ro-

tatable sleeve 13. The crankpin 58 is preferably revolved at a slightly slower speed than the rotation of the lap 30. A slow speed drive is provided for the cage reciprocating mechanism so that the work pieces will be reciprocated slowly across the operative face of the rotatable lapping wheel. In the preferred construction, a gear 69 is keyed to the lower end of the rotatable sleeve 13. The gear 60 meshes with a gear 61 which is rotatably mounted on a stud 62. A gear 63 is keyed to rotate with the gear 61 and meshes with a large gear 64 mounted on the lower end of the rotatable shaft 55. When the motor 16 is rotated to drive the worm gear 23 and cause a rotation of the lapping wheel 11, the rotation of the sleeve 13 serves through the gear 60, the gear 61, the gear 63, and the gear 64, to rotate the shaft 55 and the head 54 to revolve the crankpin 50. During this movement, the enlarged head 51 slides within the elongated slot 52 and produces a reciprocatory movement of the work carrying cage 30.

It is desirable to provide a suitable work holding device so that the work pieces may be held in operative lapping contact with the lapping wheel 11 at a desired and predetermined pressure. It is also desirable to provide a plurality of loading stations for the cage in which a plurality of work pieces may be loaded into the cage or unloaded therefrom while the lapping operation on the remaining pieces continues, that is, to permit loading one section of the cage after a predetermined lapping operation has been performed on a plurality of work pieces while the machine continues in operation, lapping a plurality of other pieces of work. This mechanism may comprise a plurality of work holding plates 70 which are preferably pivotally mounted by means of pivot pins 71 to a central portion 72 which is fixed to the cage 30. The work holding plates 70 are each provided with a plurality of spring pressed plungers 75 which are slidably supported in bushings 76 on the plate 70. The plungers 75 are provided with enlarged heads 77 which are arranged to engage the upper surface of the work piece. A spring 78 surrounds the plungers 75 and is interposed between the bushing 76 and the head 77. The spring-pressed plungers are arranged to apply a desired pressure at the central portion of the work piece to be lapped. Each of the work holding plates 70 is provided with an actuating handle 80 and may be held in an operating position to hold the work pieces in operative relation with the lap 11 by means of a latch 81 which is pivotally mounted on a stud 82 carried by the cage 30. A spring 83 serves to rock the latch 81 into the position illustrated in Fig. 3 to hold the plate 70 so as to apply a predetermined pressure to each of the work pieces 31 during the lapping operation. In order to remove the lapped pieces of work from the machine after a predetermined lapping operation, the latch 81 may be moved in a counterclockwise direction to release the plate 70 and the handle 80 may then be raised to rock the plate 70 about its pivot pin 71 so that the work pieces 31 may be readily removed from the aperture within the cage 30. Each of the work holding plates 70 is provided with an operating handle 80 and a latch 81 so that each plate may be individually released or latched in an operating position. By providing a construction of this type, a plurality of work pieces may be removed from the machine while the machine 75 is operating and lapping the remaining pieces of

work held by the cage 30, thereby permitting removal of finish lapped pieces of work and inserting new pieces to be lapped while the machine is in continuous operation.

To facilitate loading and unloading of work pieces from the lapping machine, it is desirable to provide a suitable mechanism for indexing the cage member 30 so that the various sections of the cage may be readily unloaded and loaded from a single operating station in front of the machine. To accomplish this result, the pan-shaped member 37 is preferably rotatably supported on the base 10. The base 10 is provided with a track 85 having a plurality of rollers 86 mounted therein and which serve as an anti-friction bearing for the pan-shaped member 37. An annular ring-shaped member 87 is fixedly mounted on the under side of the pan 37 and has a projecting flange 88 which engages the under side of the track 85 and serves as a guide to prevent lifting of the pan-shaped member 37. The annular ring 88 is provided with a beveled gear 89 at its lower surface which meshes with a bevel gear 90 carried by a rotatable shaft 91 which is supported in a bearing 92 in a frame 94. A driving motor 93 is supported on the frame 94 and is provided with a pulley 95 which drives a pulley 96 by means of a belt 97. The pulley 96 is supported on one end of a rotatable shaft 98. A one-revolution clutch 99 is interposed between the shaft 91 and the shaft 98. This clutch may be actuated by means of a lever 100. The gear ratio between the gears 89 and 90 and the drive between the electric motor 93 and the shaft 98 are such that when the control lever 100 is moved to engage the one-revolution clutch 99, the pan 37 and the cage 30 will be indexed one station to bring the operating handle 80 into a position for unloading finish lapped pieces of work and replacing them with new pieces to be lapped without the necessity of stopping the rotation of the lap or the movement of the work carrying cage.

The one-revolution clutch is of a standard well known type, such as that known as the Conway one revolution clutch. This clutch may comprise a cylindrical member 101 which is keyed to the shaft 98 and is surrounded by a band 102 which is connected by a flange 103 with an integrally formed sleeve 104 which is rotatably supported on the shaft 91. The lever 100 is formed integral with a cam member 105. A lever 106 is pivotally mounted on the band 102 and serves when rocked in a counterclockwise direction (Fig. 4) to tighten the band 102 on the member 101 and to thereby transmit motion from the motor 93 to the gear 90 to rotate the gear 90 and the gear 89 to index the cage 30 and pan 37 one station. The arm 106 is provided with a rotatable roller 107 which rides on the cam 105. When the roller 107 is in the depressed portion of the cam, as illustrated in Fig. 4, the band 102 does not bind on the sleeve 101 and no motion is transmitted from the motor to the shaft 91. When the lever 100 is rocked in a counterclockwise direction (Fig. 4), the cam 105 rotates and the roller 107 rides up onto the concentric portion of the cam 105, thereby rocking the arm 106 in a counterclockwise direction, and serves to tighten the band 102 on the sleeve 101 to transmit power to the shaft 91. Power is transmitted to the shaft 91 until the roller 107 is revolved one complete revolution and again dropped into the depressed portion of the cam 105, thereby releasing the clutch band and stop- 75

ping the rotation of the cam 37 and the cage at the next loading and unloading station.

It is desirable to provide a suitable means for applying abradant material for a lapping operation. This mechanism may comprise an electric motor 110 which serves to rotate a pump 111 contained within a reservoir 112. The reservoir 112 preferably contains a mixture of a lubricant and a fine abrasive or lapping powder. The pump 111 draws the fluid and abrasive from the reservoir 112 and forces it through a pipe 113 and through a nozzle 114 to the lapping plate 11.

It is desirable to stop the flow of abrading material during the lapping operation. This is preferably accomplished by providing a standard gate valve, such as a spring opened, trip closed valve 115 which may be automatically actuated by a stud 116, one of which is carried by each of the plates 70, so that when the cage and pan are indexed to a new loading position, the valve 115 is automatically shut off to stop the flow of abradant fluid.

A suitable means is provided for agitating the fluid and abrasive so that the fluid passing through the pump contains a substantially uniform quantity of abrasive. This is preferably accomplished by providing a by-pass pipe 117 which by-passes a portion of the fluid and abrasive from the pump 111 and forces it out through holes 118 in a pipe adjacent to the bottom of the reservoir 112. Fluid under pressure passing through the holes 118 serves to continuously agitate the fluid and abrasive during the lapping operation to obtain a more or less uniform distribution of the abrasive within the lubricant.

While in the drawings the work cage has been illustrated as being supplied with apertures of a uniform size to lap the same size work piece, it is readily apparent from the foregoing disclosure that, if desired, a plurality of varying sizes and shapes of work pieces may be simultaneously lapped, if desired. It is only necessary to provide cage apertures of the desired shape and size to accommodate the work pieces to be lapped.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:—

1. A lapping machine comprising a rotatable lapping wheel having a plane operative surface, means to rotate said lapping wheel, a work cage arranged simultaneously to hold a plurality of work pieces in operative relation with said lapping wheel, means to move said cage relative to said wheel during the lapping operation, and means to index said cage to facilitate loading of the same without stopping the movement of the cage or the rotation of the lapping wheel.

2. A lapping machine comprising a rotatable lapping wheel having a plane operative face, means to rotate said lapping wheel, a work carrying cage, a plurality of work receiving apertures therein arranged simultaneously to hold a plurality of work pieces in operative relation with said lapping wheel, means to cause a relative movement between the cage and rotatable lapping wheel, and means including an indexing

mechanism to index the cage through a partial rotation to facilitate loading of the same without stopping the lapping operation.

3. A lapping machine comprising a rotatable lapping wheel having a plane operative face, means to rotate said lapping wheel, a work cage, a plurality of work receiving apertures therein arranged simultaneously to hold a plurality of work pieces in operative relation with said lapping wheel, means to reciprocate said cage to carry the work pieces across the face of the lapping wheel, and means to index said cage to facilitate loading of the same without stopping the reciprocation of the cage or the rotation of the lapping wheel.

4. A lapping machine comprising a rotatable lapping wheel having a plane operative face, means to rotate said lapping wheel, a work carrying cage, a plurality of work receiving apertures therein arranged simultaneously to hold a plurality of work pieces in operative relation with said lapping wheel, said apertures being arranged in spaced groups, means to reciprocate said cage to carry the work pieces across the operative face of the lapping wheel, means including a power driven indexing mechanism intermittently to index said cage through a partial rotation to move groups of apertures successively to a loading position without stopping either the movement of the cage or the lapping wheel.

5. A lapping machine comprising a rotatable lapping wheel having a plane operative face, means to rotate said lapping wheel, a work cage, a plurality of work receiving apertures therein arranged to hold a plurality of work pieces in simultaneous lapping engagement with said wheel, said apertures being arranged in groups, means to reciprocate said cage to carry the work pieces across the face of said lapping wheel, means to yieldably hold said work pieces in operative engagement with said lapping wheel, and an indexing mechanism operatively connected intermittently to index said cage to move groups of apertures successively to a loading position and thereby facilitate removal and insertion of work pieces before and after a lapping operation.

6. A lapping machine for simultaneously lapping a surface on a plurality of work pieces comprising a rotatable lapping wheel having a plane operative face, means to rotate said lapping wheel, a work carrying cage, a plurality of spaced apertures therein arranged to hold a plurality of work pieces simultaneously in operative relation with said lapping wheel, said apertures being arranged in spaced groups, means to reciprocate said cage to carry the work pieces across the lapping wheel, and means including a power driven manually controlled indexing mechanism to intermittently index said cage to facilitate loading portions of the cage without stopping the lapping operation on parts located in other portions of said cage.

7. A lapping machine comprising a rotatable lapping wheel, means to rotate said lapping wheel, a work carrying cage, a plurality of work receiving apertures therein arranged to hold a plurality of work pieces in operative relation with said lapping wheel, said apertures being arranged in spaced groups, means including a plurality of independent work holding plates carried by said cage each arranged to hold a group of said work pieces in engagement with said lapping surface, and means including a latch to independently hold said plates in an operating position.

8. A lapping machine comprising a rotatable

- lapping wheel, means to rotate said wheel, a work carrying cage, a plurality of work receiving apertures therein arranged to hold a plurality of work pieces in operative relation with said lapping wheel, said apertures being arranged in spaced groups, means to cause a relative movement between the cage and the rotatable lapping wheel, a plurality of independent work holding plates carried by said cage and each arranged to hold a group of said work pieces in engagement with said lapping surface under a predetermined pressure, and means to independently latch or release said plates in an operating position.

9. A lapping machine comprising a rotatable lapping wheel, means to rotate said wheel, a work carrying cage arranged to hold a plurality of work pieces in operative relation with said lapping wheel, means to cause a relative movement between the cage and the rotatable lapping wheel, a plurality of independent work holding plates carried by said cage and arranged to hold a plurality of said work pieces in engagement with said lapping surface under a predetermined pressure, means to independently latch or release said plates in an operating position, and means including an indexing mechanism intermittently to index the cage through a partial rotation to facilitate loading of the same without stopping the lapping operation.

10. A lapping machine comprising a rotatable lapping wheel, means to rotate said lapping wheel, a work carrying cage, a plurality of work receiving apertures therein arranged to hold a plurality of work pieces simultaneously in operative relation with said lapping wheel, said apertures being arranged in spaced groups on said cage, means to reciprocate said cage relative to said rotatable lapping wheel, means to hold said cage in a predetermined spaced relationship with said lapping wheel, means including a plurality of pivotally mounted pressure plates carried by said cage, and means to latch said plates in an operating position, each plate being arranged to simultaneously hold a group of work pieces in operative relation with the lapping wheel for a lapping operation.

11. A lapping machine comprising a rotatable lapping wheel, means to rotate said lapping wheel, a work carrying cage, a plurality of work receiving apertures therein arranged to hold a plurality of work pieces in operative relation with said lapping wheel, said apertures being arranged in spaced groups on said cage, means to cause a relative movement between the cage and rotatable lapping wheel, means to hold said cage in a predetermined spaced relationship with said lapping wheel, means including a plurality of pivotally mounted pressure plates carried by said cage and arranged to be latched in an operating position to simultaneously hold a group of work pieces in operative relation with the lapping wheel for a lapping operation, and means including an indexing mechanism intermittently to index the cage through a partial rotation to facilitate loading of the same without stopping the lapping operation.

12. A lapping machine comprising a rotatable lapping wheel, means to rotate said lapping wheel, a plurality of work receiving apertures therein, a work carrying cage to hold a plurality of work pieces simultaneously in operative relation with said lapping wheel, said apertures being arranged in spaced groups on said cage, means to reciprocate said cage relative to said rotatable lapping wheel, means to hold said cage in a predetermined spaced relationship with said lapping wheel, means including a plurality of pivotally mounted pressure plates carried by said cage and arranged to be latched in an operating position to simultaneously hold a group of work pieces in operative relation with the lapping wheel for a lapping operation, and means including a power driven one revolution clutch to index said cage to bring successive work holding plates into a loading position to facilitate loading of the cage without stopping the lapping operation.

13. A lapping machine comprising a rotatable lapping wheel, means to rotate said lapping wheel, a work carrying cage, a plurality of work receiving apertures therein to hold a plurality of work pieces simultaneously in operative relation with said lapping wheel, said apertures being arranged in spaced groups, means to guide said cage for a reciprocatory movement relative to said lapping wheel, means to reciprocate said cage relative to the rotatable lapping wheel, a plurality of independently movable work holding plates carried by said cage, each being arranged to independently hold a plurality of work pieces in operative relation with the lapping wheel, and means including a power driven indexing mechanism to index the cage through a partial rotation to facilitate loading of the same at a single operating station without stopping the lapping operation.

14. A lapping machine comprising a rotatable lapping wheel, means to rotate said lapping wheel, a work carrying cage, a plurality of work receiving apertures therein to hold a plurality of work pieces simultaneously in operative relation with said lapping wheel, said apertures being arranged in spaced groups, means including a plurality of elongated slots and pins to guide said cage for a reciprocatory movement relative to said lapping wheel, means to positively reciprocate said cage, adjustable means to hold said cage in spaced relationship with the operative surface of said lap, and means to index said cage through a partial rotation to facilitate loading of the same without stopping the lapping operation.

15. A lapping machine comprising a rotatable lapping wheel, means to rotate said lapping wheel, a work carrying cage, a plurality of work receiving apertures therein to hold a plurality of work pieces simultaneously in operative relation with said lapping wheel, said apertures being arranged in spaced groups, a plurality of independent pivotally mounted work holding plates each arranged to yieldably maintain a group of work pieces in operative relation with the lapping wheel, adjustable means to hold said cage in spaced relationship with the operative face of the lapping wheel, means to guide said cage for a reciprocatory movement relative to the lapping wheel, means to reciprocate said cage, and means including a manually operable one revolution clutch to index said cage to bring successive work holding plates into a loading position to facilitate loading of the cage without stopping the lapping operation.

HERBERT S. INDGE
